UNITED STATES PATENT OFFICE

2,551,468

DOUBLE DOCUMENT CONTROL FOR PHOTOGRAPHING MACHINES

Friedrich J. Schutt, Brooklyn, N. Y., assignor to Remington Rand Inc., New York, N. Y., a corporation of Delaware

Original application March 30, 1944, Serial No. 528,682. Divided and this application January 7, 1948, Serial No. 895

9 Claims. (Cl. 271—57.)

1

The present invention relates to improvements in sheet feeding means primarily for use in document photographing machines, and more particularly to a mechanism operable to control document feed whenever more than one document is fed at one time.

This application is a division of application Serial No. 528,682, filed March 30, 1944, Patent No. 2,452,497 granted October 26, 1948.

The sheet feeding means according to the present invention comprises a pair of feed rollers, at least one of which is drivable, adapted and arranged to grip a sheet for feeding between them, one of said rollers being mounted on a shaft at a point intermediate the ends thereof, which shaft, on the rollers encountering an excessive document thickness, is adapted and arranged to rock about a fulcrum at or near one of its ends for operation by substantially its other end of a control device for interrupting document feed. Since the control device is more remote from the fulcrum point of the shaft than is the feed roller of that shaft therefrom, it follows that movement of that end of the shaft remote from the fulcrum is correspondingly greater than the actual separation of the feed rollers thus making it possible to provide a control which is very sensitive to varying document thickness and which is quick in operation.

In the drawings:

Fig. 1 shows the document feed mechanism for a document photographing machine embodying the present invention in side elevation looking from the right-hand side of the machine, the casing of the machine being omitted for convenience in illustrating the main drive mechanism for the document feed.

Fig. 2 is an enlarged fragmentary side elevation of the upper front portion of the document feed mechanism of the machine looking from the left-hand side of the machine, the outer casing for the machine being omitted.

Fig. 3 is an enlarged fragmentary front elevation with the central portion of the document feed mechanism omitted, the casing being omitted for illustrating the portions of the main drive mechanism mounted in the side walls at the front of the machine, with the document feed control mechanism and thickness control mechanism shown in front elevation and part of the index mechanism being omitted for clarity.

Fig. 4 is an enlarged fragmentary vertical section taken substantially on line 4—4 of Fig. 3 looking toward the inside of the left-hand side wall.

2

Fig. 5 is an enlarged fragmentary vertical section taken substantially on line 5—5 of Fig. 6 looking toward the inside of the right-hand side wall.

Fig. 6 is an enlarged detail cross-section taken substantially on line 6—6 of Fig. 1 showing the double document control mechanism.

Fig. 7 is a vertical cross-section taken substantially on line 7—7 of Fig. 6.

The general construction of the document photographing machine employing the present invention is disclosed in copending application, Serial No. 528,683, filed on March 30, 1944 and Patent Number 2,377,525 dated June 5, 1945, and the aforesaid Patent No. 2,452,497, and the said general construction is illustrated and described herein only to the extent necessary to describe the correlation between the structure disclosed in the respective patent and application.

20 The document photographing machine disclosed in the aforementioned Patent No. 2,452,497, discloses a frame structure for supporting the various mechanisms of the machine having side walls at the front ends of the base portion for supporting the document feed, the illuminating means, and the control mechanism for the machine.

Right and left-hand side walls 1 and 2 correspond to the side walls shown in the aforementioned applications.

30 The document feed mechanism has end plates 3 mounted in spaced parallel relation for supporting a plurality of spaced parallel arcuate guide bars 4, Fig. 6, to provide a curved path for guiding documents thereover from the top to the bottom portions thereof in a manner disclosed in the aforesaid Patent No. 2,377,525. End plates 3 mount a plurality of feed shafts 5 carrying document feed rolls 6 rigidly mounted thereon in spaced relation and having the peripheries extending between arcuate guide bars 4 with a portion of the periphery of each feed roll extending beyond the outer periphery of arcuate guide bars 4 for engaging and feeding documents over the upper surfaces of said guide bars. Feed shafts 5 are journaled in end plates 3 and at the right-hand ends, as shown in Fig. 3, the shafts project through an opening in end plate 1 indicated at 7 in Fig. 1 where each shaft carries a small gear 8 intermeshing with internal gear 9 of main drive gear 10.

40 Main drive gear 10 is rigidly mounted on main drive shaft 11 extending transversely across the front of the machine between side walls 1 and 2

45 50 55 and beyond the outer side thereof, as shown in

Fig. 1. Main drive gear 10 is journaled in end plate 3 and at the right-hand end of main drive shaft 11, as shown in Fig. 3, the shaft carrying a small gear 12 intermeshing with internal gear 13 of

Fig. 1. A main drive pulley 12 is driven by an electric motor, not shown, through belt 13. Pulley 12 is mounted on a stub-shaft carried by side wall 1 and carries a pinion 14 intermeshing with gear 15 mounted on another stub-shaft carried by side wall 1 and having clutch controlled driving connection with gear 16 intermeshing with the external gear teeth 17 on main drive gear 10.

The clutch control for the driving connection between gears 15 and 16 has a pair of clutch collar operating arms 18 carried by rod 19 rotatably mounted in bearing bracket 20 secured to the outer side of the side wall 1. A lever 21 is mounted on the end of rod 19 at the opposite side of the bearing from clutch collar operating arms 18, as shown in Fig. 1, and has the free end thereof connected with the armature of solenoid 22. The clutch is disengaged when the solenoid is energized. When solenoid 22 is not energized a coil spring 23 having opposite ends secured to lever 21 and side wall 1 respectively, as shown in Fig. 1, operates lever 21 to rotate rod 19 and maintain the clutch in engaged relation for driving main drive gear 10 in the rotation of main drive pulley 12 by the motor.

Upper and lower document guide units, seen in dotted lines in Fig. 1 at 24 and 25 respectively, have a plurality of arcuate guide bars 26 mounted in spaced parallel relation between and supported by end members 27. Upper and lower guide units 24 and 25 carry a plurality of feed shafts 28 each mounting a plurality of document feed rolls 29 arranged to have the peripheries thereof extend between guide bars 26 in registry with feed rolls 6. As described in the aforesaid Patent No. 2,452,497 the guide units 24 and 25 define a path of travel through which a document to be photographed is fed into and through the photographing position by the cooperating sets of rollers 6 and 29 which (with the exception of the top, or leading set of those rollers, which may conveniently be regarded as the entrance rollers and which are those shown in the instant disclosure), are spring loaded into peripheral engagement for gripping and thereby feeding a document engaged between them through the path defined by the guide units.

A supporting rod 30 extends through the upper front corners of upper guide member 24 and has the free ends detachably engaged in openings in side walls 1 and 2 for pivotally supporting upper guide member 24 in transversely extending relation between side walls 1 and 2. A suitable latch member having latch rods 31 secures the lower rear end of upper guide member 24 in operative position, as shown in Fig. 1. A pair of supporting rods 32 engaged in transversely extending relation through end members 27 of the lower guide member 25 removably mounts the lower guide member in operative position between side walls 1 and 2. End plates 3 have projecting portions mounted on a supporting rod secured at opposite ends in side walls 1 and 2 as shown in Patent No. 2,452,497. The right-hand end plate 3 has an aperture in the central portion for engagement over a supporting stud carried by a portion of side wall 1 projecting toward main drive shaft 11 as indicated in Fig. 1 at 7'. This provides for detachable mounting of the main document feed unit between side walls 1 and 2. The path for feeding documents is arranged in concentric relation to main drive shaft 11 having roller bearing mountings in end plates 3. Documents enter the feed unit at the top as indicated at A, Fig.

1, and after passing through a semi-circular path past the photographing position are discharged at the bottom of the unit at B.

The double document control mechanism 5 which is the essential feature of the present invention is associated with the shafts 5 and 25. The entrance rollers 6 and 29 on their respective shafts 5 and 29, as distinct from the remaining cooperating groups of such rollers on the other shafts forming part of the document guide units 24 and 25, are deliberately spaced so that there is clearance between their registering but non-contacting peripheries. The shafts 5 and 28 furthermore differ from the other shafts in that the uppermost feed shaft 5 of the main feed unit is provided in the central portion of its length with a center metallic feed roll 64 as shown in Fig. 6, whereas the upper feed shaft in the upper guide unit 24 arranged in paired relation with the shaft 5 has a centrally located metallic feed roll 65 thereon for peripheral engagement with feed roll 64 while the remaining feed rolls on this upper shaft do not have peripheral engagement with the corresponding feed rolls 6, as shown in Fig. 6. Opposite ends of the uppermost feed shaft 28 are mounted in bearing sleeves 66 carried by slideable blocks 67 engaged between the spaced plates of end members 27. Guide slots 68 in the plates of end members 27 slidably mount bearing sleeves 66 for movement of the shaft 28 with its rollers 29 and 65 towards and away from the shaft 5 with its rollers 6 and 64 and laterally extending pins 69 project laterally outwardly through the guide slots 68 in end members 27.

At the right side of the machine the free end of pin 69 engages one end of a bell crank lever 70 pivoted at 71 on a stud projecting inwardly from the inner face of side wall 1 while the upper end of bell crank 70 has a projection 72 engaging a thickness control cam 73. Thickness control cam 73 is mounted on the inner end of an adjusting shaft 74 having the central portion rotatably mounted in a bracket 75 secured to the outer face of side wall 1. The outer end of adjusting shaft 74 carries a member 76 adapted for manual rotation to adjust the position of eccentric 73. A ratchet wheel 77 is mounted adjacent the inner end of member 76 and has the free end of a spring actuated pawl 78 resiliently engaged therewith for normally holding adjusting shaft 74 against rotation. Pawl 78 is pivotally mounted on bracket 75, as shown in Fig. 7.

There are ten teeth on ratchet wheel 77 in order that pawl 78 will operate to normally hold the ratchet wheel against rotation by member 76 in a predetermined position for each adjacent pair of teeth until the spring pressure of pawl 78 is manually overcome by positive manual rotation of member 76. Member 76 is in the form of an annular disc having a knurled periphery, as shown in Fig. 3, with a cylindrical portion adjacent the disc provided with indicia at 79 showing the position of thickness adjustment of member 76. The numerals indicating the adjustment run from one to ten and represent thickness adjustments for sheets determining positions of adjustment where sheets of different thickness will be either fed through the machine or prevented from being fed by stopping the feed.

A bell crank lever 80, Fig. 5, is pivoted against the inner side of right-hand side wall 1 in front of the upwardly extending arm of bell crank lever 70, as shown in Fig. 5, on a stud projecting

inwardly from side wall 1. One arm of bell crank 80 extends upwardly and has a pin 81 on the upper end extending laterally and engaging the forward edge of the upwardly extending arm of bell crank 70. The other arm of bell crank 80 extends rearwardly and has one end of a coil spring 82 connected to the end thereof. The opposite end of coil spring 82 is connected to one end of lever 83 extending radially from document straightening shaft 84 carrying document straightening fingers 85 for engaging the leading edge of a document immediately after it is fed into the feed mechanism between rolls 64 and 65. It will be noted that the periphery of the roll 65 is convexly arcuate, having line contact with the upper face of a document engaged between it and the roll 64. Thus, if a document is fed between the rolls 64 and 65 with its leading edge not truly transverse to the direction of feed, the more advanced end of the leading edge will engage the straightening fingers at that end to be momentarily arrested. Meanwhile the line contact of the roll 65 with the document permits it to swing until the entire leading edge engages all of the fingers 85 when further feeding of the document will move fingers 85 and rock shaft 84 against the tension of spring 82 until the straightened document passes under the ends of the fingers. The straightened documents will then be guided through the feed mechanism with the leading edges in transversely extending relation. Coil spring 82 also operates simultaneously to maintain bell crank 80 with pin 81 in engagement with the upper end of bell crank 70 for maintaining projection 72 in constant engagement with the surface of eccentric 73. The lower end of bell crank 70 extends rearwardly and the rear free thereof engages above laterally extending pin 69 at the right-hand side of the machine on slidable block 67 for holding the slidable block against upward movement. The spring 82, being operatively connected between the bell crank 80 and the lever 83 which mounts the straightening finger shaft 84, has an additional function. In that respect, as will be seen from Fig. 5, anti-clockwise rotation of the cam 73 to set the double document control to accommodate thicker documents as will later be described, swings the bell crank 70 clockwise about its pivot 71 and, since the upper end of the bell crank 70 engages the pin 81 of the bell crank 80, it follows that bell crank 80 also then swings clockwise about its pivot, thereby increasing the tension in the spring 82. Thus the tension of spring 82 increases correspondingly with the setting of the double document control to accommodate thicker documents, thereby tending to prevent premature release of the straightening fingers such as might otherwise occur when controlling the feed of thick documents.

As seen in Figs. 6 and 7 the control wheel 16 is set to accommodate only a single thickness relatively thin document. At that setting should overlapping documents be engaged between the feed rolls 64 and 65 the excessive document thickness will tend to lift the shaft as a whole but since there is negligible if any clearance between the right hand pin 69 and the under side of the rearwardly extending arm of the bell crank lever 70 the shaft will in effect rock about the fulcrum point constituted by the pin contacting portion of the lower edge of the said rearwardly extending arm of the bell crank 70. Since the right-hand pin 69 can then rise no further, rocking of the

shaft due to the excessive document thickness then manifests itself as rising movement at the left-hand end of the shaft 28 and furthermore, since the roller 65 is approximately midway along the shaft 28, the left end half of the shaft, due to its greater distance from the fulcrum point, rises to a considerably greater extent than the thickness of the engaged documents. The rising movement of the pin 69 at the left-hand end of the shaft 28 is utilized to operate switch control bell crank 86 pivotally mounted on bracket 87 on the outside face of left-hand side wall 2. A short substantially horizontally extending arm 88 on bell crank 86 extends inwardly through an opening in side wall 2 and is formed with an extension for engagement with the top peripheral portion of the projection 69 on left-hand slide block 67, Fig. 6. A coil spring 89 secured at one end to short arm 88 of bell crank 86 and at the opposite end to a stud on the inner face of side wall 2 firmly maintains the end of arm 88 engaged with left-hand projection 69 to maintain feed and control roll 65 in resilient rolling contact with roll 64. The other arm 90 of bell crank 86 extends upwardly along the outside of left-hand side wall 2, as shown in Figs. 3 and 6, and has the free end provided with a lateral projection for engaging the operating pin of micro-switch 91 mounted on the upper portion of bracket 87, as shown in Figs. 2, 3 and 6.

In the counter-clockwise rotation of bell crank 86 through the raising of pin 69 by a document engaging between feed and control rolls 64 and 65, it will be seen that by controlling the position of the fulcrum for upper shaft 28 at the right-hand end, the amount of vertical movement at the left-hand end of the control shaft can be utilized to actuate micro-switch 91 to close the circuit thereto and actuate control means for stopping the feed of documents whenever the document thickness is greater than the amount for which the knob 76 is set. Micro-switch 91 is connected in the electrical circuit with solenoid 22, so that whenever the switch is closed, the solenoid will be energized to disconnect and stop the feed mechanism from operating so that documents cannot be fed through the feed mechanism beyond rolls 64 and 65.

If thicker documents are to be fed, the adjustment wheel 16 is turned anti-clockwise as viewed in Figs. 5 and 7 to bring a correspondingly higher portion of the cam 73 into engagement with the projection 72 of the bell crank 70. The resulting movement of the bell crank 70 lifts its rearwardly extending arm off the pin 69 at the right-hand end of the shaft 28 and a corresponding increase of separation of the feed rollers 64 and 65 is then necessary before the right-hand pin 69 engages the rearwardly extending arm of the bell crank 70 and before the shaft is constrained to rock about the fulcrum for actuation of the switch 91. Whatever the setting of the double thickness adjustment, the fact remains that due to the distance of the left-hand end of the shaft 28 from the fulcrum point being so much greater than the distance of the feed roller 65 from the same fulcrum point, the rise at the left-hand end of the shaft is much greater than any excessive document thickness encountered between the feed rollers 64 and 65. Consequently an extremely sensitive control is provided which is so quick in action that only the leading edge of documents of a greater thickness than that for which the control is set will engage between feed and control rolls 64 and 65 before the feed mech-

anism actually stops. This provides for convenient manual removal of the documents at the top front portion of the feed mechanism by the machine operator resulting in the feed mechanism being restored to operation so the operator can again feed the documents into the machine in proper order. The mechanism prevents the feeding of two or more documents simultaneously and also the feeding of documents that are folded or of a greater thickness than is provided for by the setting of control knob 76. The control mechanism may control the operation of the feed in any suitable manner such as just described and shown in either of the copending applications hereinabove mentioned whether the feed of documents be manual or mechanical.

The invention claimed is:

1. In a document photographing machine, document feed means for feeding documents through a photographing position, drive means for operating said document feed means, and means for controlling operation of said document feed means by said drive means having a shaft extending transversely to the direction of document feed, a document engaging member mounted on said shaft intermediate the ends and engaging a part of said document feed means and movable away from said part by the thickness of a document, a support at one end of said shaft providing a fulcrum for said shaft, and means movably supporting the opposite end of said shaft for engaging and operating said controlling means for stopping the document feed when documents of greater than a predetermined thickness engage between said member and part.

2. In a document photographing machine, document feed means for feeding a document through a photographing position, drive means for operating said document feed means, and means for controlling operation of said document feed means by said drive means having a shaft extending transversely to the direction of document feed, a document engaging member mounted on said shaft intermediate the ends and engaging a part of said document feed means and movable away from said part by the thickness of a document, bearings rotatably mounting said shaft at opposite ends, a support slidably mounting said bearings, means at one end of said shaft for controlling slidable movement of said bearing to provide a fulcrum for the movement of said shaft at one end thereof, and means operated by the bearing at the opposite end of said shaft for operating said controlling means to stop the feed of documents when documents greater than a predetermined thickness engage between said engaging member and said part.

3. In a document photographing machine, document feed means for feeding a document through a photographing position, drive means for operating said document feed means, and means for controlling operation of said document feed means by said drive means having a shaft extending transversely to the direction of document feed, a document engaging member mounted on said shaft intermediate the ends and engaging a part of said document feed means and movable away from said part by the thickness of a document, bearings rotatably mounting said shaft at opposite ends, a support slidably mounting said bearings with opposite ends of said shaft for movement radially relative to said part of said feed means, slide members movable with said bearings and the ends of said shaft on said support, a lever engaging one of said slide mem-

bers for limiting sliding movement at one end of said shaft, means for holding said lever in adjusted position, and means operated by the slide member at the opposite end of the shaft for operating said controlling means to stop document feed when documents exceeding a predetermined thickness engage between said member and part.

4. In a document photographing machine, document feed means for feeding a document through a photographing position, drive means for operating said document feed means, and means for controlling operation of said document feed means by said drive means having a shaft extending transversely to the direction of document feed, a document engaging member mounted on said shaft intermediate the ends and engaging a part of said document feed means and movable away from said part by the thickness of a document, bearings rotatably mounting said shaft at opposite ends, a support slidably mounting opposite ends of said shaft and bearings for movement radially relative to said part of said feed means, slide members movable with the ends of said shaft on said support, a lever engaging one of said slide members for limiting sliding movement at one end of said shaft, a cam rotatably mounted on said support engaging said lever and operable for changing the position of said lever, and means operated by the slide member at the opposite end of the shaft for operating said controlling means to stop document feed when documents exceeding the thickness for which said cam is set engage between said member and part.

5. In a document photographing machine, document feed means for feeding a document through a photographing position, drive means for operating said document feed means, and a shaft for controlling operation of said document feed means by said drive means, a document engaging member mounted on said shaft intermediate the ends and engaging a part of said document feed means for document feeding cooperation therewith and movable away from said part by the thickness of a document, means rotatably mounting said shaft at opposite ends for sliding movement toward and away from said document feed means, a fulcrum means for one end of said shaft, a cam rotatably mounted on said mounting means and operable to adjust said fulcrum means for said shaft, and means operated by the opposite end of said shaft for operating said controlling means to stop document feed when documents exceeding the thickness for which said cam is set engage between said member and part.

6. In a document photographing machine, document feed means for feeding documents through a photographing position drive means for operating said document feed means, operating control means for said document feed means including a shaft extending transversely to the direction of document feed, a document-engaging member mounted on said shaft intermediate the ends and engaging a part of said document feed means and movable away from said part by the thickness of a document, bearings rotatably mounting said shaft at opposite ends, a support slidably mounting said bearings, means on one end of said shaft for controlling sliding movement of said bearings to provide a fulcrum for the movement of said shaft at one end thereof, and control means operated by the other end of said shaft responsive to the engagement of a document exceeding a predetermined thickness between said document-engaging member and said part of said document control means for moving said mem-

ber from contact with said part to stop feed of documents engaged with said part.

7. In a document photographing machine, document feed means for feeding documents through a photographing position, drive means for operating said document feed means, and means for controlling operation of said document feed means by said drive means having a yieldably mounted shaft extending transversely to the direction of document feed, a document engaging member mounted on said shaft intermediate the ends thereof and engaging a part of said document feed means and movable away from said part by the thickness of the document, means limiting the yielding movement of one end of said shaft and control means operated by the amplified yielding of the other end of said shaft responsive to engagement of a document exceeding a predetermined thickness between said document engaging member and said part of said document feed means for stopping document feed.

8. Sheet feeding means including drive means, feed means drivable by said drive means and co-operative to grip and feed sheet between them, control means for controlling said feed means by said drive means, and a document engaging member engaging a part of said document feed means and movable away from said part by the thickness of a document for operation of said control means to interrupt the feed when a sheet of greater than predetermined thickness is engaged between said part and said member, characterized by the fact that said document engaging member is mounted intermediate the ends of a yieldably mounted shaft selectively pivotal about one end and having its other end operatively connected with said control means.

9. In a document photographing machine, document feed means for feeding a document through a photographing position and drive means for operating said document feed means, the combination of means for controlling operation of said document feed means by said drive means having a yieldably mounted shaft extend-

ing transversely to the direction of document feed, a document engaging roller mounted on said shaft intermediate the ends thereof rotatable by and in substantially point contact with a document engaged between said roller and a part of said document feed means, said roller and said shaft therewith being yieldably movable away from said part by the thickness of the document, means limiting the yielding movement of one end of said shaft control means operated by the amplified yielding of the other end of said shaft responsive to engagement of a document exceeding a predetermined thickness between said roller and said part for stopping document feed, and thickness control adjustment means operable for adjusting the operational relationship of said shaft with respect to said control means for normally feeding documents of less than predetermined thicknesses, with document straightening means comprising fingers spaced transversely across the path of document feed and normally intersecting said path in advance of said photographing position, means mounting said fingers for swinging out of said path about an axis transverse to the direction of document feed, and resilient means resisting said swinging movement of said fingers until all of said fingers are engaged by a leading edge of a document in said path, said resilient means being operatively connected between said thickness control adjustment means and said fingers to increase resistance of said fingers to said swinging movement in proportion to the thickness of documents engaged thereby.
